To all whom it may concern:

Be it known that I, John Markestein, a citizen
of the United States, being a resident of
North Riverside, county of Cook, State of Illinois,
have invented a new, original, and ornamental
Design for a Locomotive Body, of which the following
is a specification, reference being made to

of.

In the drawing:

Fig. 1 is a plan view of a locomotive body,
showing my design.

Fig. 2 is a side elevational view of the body.

Fig. 3 is a perspective view, as seen from a point
in front of and at the side of the body.

Fig. 4 is a front elevational view of the body.

The appearance of the side of the body opposite
to that shown is substantially the same as
that shown, and the rear end portion of the
